Primary Examiner — Barbara Fox*Assistant Examiner* — Mary Shannon Malley*(74) Attorney, Agent, or Firm* — Cooper Legal Group,
LLC; Ronald M. Kachmarik(57) **CLAIM**The ornamental design for a sterilization apparatus, as
shown and described.**DESCRIPTION**FIG. 1 is a perspective view of the sterilization apparatus,
with the arm in a first position, showing the new design;
FIG. 2 is a top view thereof, with the arm shown in a second
position;

FIG. 3 is a bottom view thereof;

FIG. 4 is a front side view thereof;

FIG. 5 is a back side view thereof;

FIG. 6 is a right view thereof;

FIG. 7 is a left view thereof;

FIG. 8 is another perspective view of FIG. 1; and,

FIG. 9 is another perspective view, with the arm shown in a
third position.The broken lines depict portions of the sterilization apparatus
that form no part of the claimed design.**1 Claim, 9 Drawing Sheets**(56)
